Alfred L. Sewell

United States Patent Office.

ALFRED L. SEWELL, OF CHICAGO, ILLINOIS.

Letters Patent No. 91,570, dated June 22, 1869.

BOOK-COVER PROTECTOR.

The Schedule referred to in these Letters Patent and making part of the same.

To all whom it may concern:

Be it known that I, ALFRED L. SEWELL, of the city of Chicago, in the county of Cook, and State of Illinois, have invented a certain new and useful Device for Protecting the Corners of Books during transportation; and I do hereby declare that the following is a full, clear, and exact description thereof, reference being had to the accompanying drawings, making a part of this specification, in which—

Figure 1 represents a book, with my device applied;

Figure 2 represents one form, detached;

Figure 3, another form, detached;

Figure 4, a blank cut for bending into the forms A and B;

Figure 5, a blank cut for forming D; and

Figure 6, a blank cut for bending into the form shown at C, of fig. 1.

The nature of my invention consists in constructing a small, light, and stiff device to fit over the corners of books, to prevent injuring them when transported singly by mail, express, or otherwise, or in small packages.

It usually happens, from the rough handling that books receive, or from heavy weights being placed on them, that the corners of the covers or lids are crushed or broken down, so as to be permanently injured. This, sometimes, also happens in storage, as well as in transit, and detracts much from the value of the books.

My device overcomes these difficulties, by providing a stiff support for the outer edges of the covers, which shall extend far enough on to the cover of the book to make the support certain, and, by carrying it around the corners, it also operates as a guard, so that by its application books may be transported with safety in paper wrappings, which is especially desirable when sending books by mail.

To enable others skilled in the art to make and use my invention, I will describe its construction and operation.

In construction, tin, brass, or any other suitable material can be used, but I usually make my supports of tin.

I first cut them out in blanks, as shown at figs. 4, 5, and 6, and then bend them as indicated by the dotted lines.

Those shown at A and B, of fig. 1, are cut as shown at fig. 4, the main difference between them being that one is soldered and the other not.

When they are soldered, the wings or braces E may be made of separate pieces if desired; but they will usually be found sufficient to answer the purpose without soldering, when cut as shown at fig. 4. When soldered, this makes the strongest form shown.

A very simple form is shown at C, which is a straight piece, with a slit, b, in each side, so that when bent, the inner ends of the flanges or wings F will cross each other, making it very convenient for soldering, if that should be desired.

Another simple form is shown at D, where the sides are cut out at a, so as to form a mitred joint when bent.

In use, the blanks may be kept on hand and bent as required for use, or they may be fully completed.

Except in cases of finely-bound books, or when they have a long distance to go, I do not usually apply my support to the backs, as they are not so much needed there. The leaves of the book will, to a considerable extent, support the covers, and they are not as liable to be broken at that point.

I have found, by experiments, that bound books may be transmitted by mail or otherwise, in paper wrappers, without injury, by the use of these supports.

Having thus fully described my invention,

What I claim, is—

A metallic protector for book-corners, constructed substantially as herein described, for the purpose of clasping the opposite corners of the book-covers, and covering the corners of the leaves intervening, and also for the purpose of being attached and removed when desired, as set forth.

ALFRED L. SEWELL.

Witnesses:

L. L. BOND,

E. A. WEST.
